CERVICAL TRACTION FRAME

James M. Greenwood, 115 N. 1st St.,
Alpena, Mich. 49707

Filed May 10, 1972, Ser. No. 252,145

Term of patent 14 years

Int. Cl. D24—02

U.S. Cl. D83—1 E

FIG.1

FIG.3

FIG.4

FIG. 1 is a perspective view of the cervical traction frame showing the front, one side and one end of my new design;

FIG. 2 is a top plan view of the cervical traction frame;

FIG. 3 is a side view of the cervical traction frame; and

FIG. 4 is an end view of the cervical traction frame. I claim:

The ornamental design for a cervical traction frame, substantially as shown and described.
